BOILER SYSTEM INCLUDING AN
ECONOMIZER

Fritz Wenge, Frankfort-on-the-Main, Germany,
assignor to Elektrizitäts-Aktion-Gesellschaft
vorm. W. Lahmeyer & Co., Frankfort-on-the-
Main, Germany

Application October 1, 1932, Serial No. 635,839
In Germany October 7, 1931

9 Claims. (Cl. 122—444)

My invention relates to a boiler system including an economizer, and more particularly to a device for protecting the economizer during the inactivity of the means for feeding water to the boiler through the economizer.

It is known to protect economizers from sudden pulsations of the pumps and water hammer by arranging the feed valves or automatic feed water regulators in front of the economizers. Such automatic means for feeding the boiler in dependence on the water level in the boiler are also provided in my system. However, when the feed valve is closed the flue gases raise the temperature of the water enclosed in the economizer. As a result, steam is formed in the economizer so that a cushion of vapour is formed between the water in the boiler and in the economizer. Now, when the feed of the boiler starts again, the feed water flows at high speed through the economizer, pushing the steam before it into the steam boiler and causing the well known water hammer which leads to disturbances in operation and sometimes even to the explosion of the economizer. Decreases in the water content of the economizer or formation of the above mentioned vapor cushion may also result from separations of gases; leakages or the like; and will produce the same disturbing effects. Devices have already been proposed intended to avoid the disadvantages resulting from the loss of water. They all possess the disadvantage, however, that they operate periodically, and because of their inertia are slow in regulation.

It is an object of my invention to provide a protecting device which is without disadvantages as set out above.

To this end, in a boiler system including an economizer and means, i. e., the automatic valve or feed water regulator in front of the economizer, for feeding water to the boiler through the economizer in dependence on the water level in the boiler, I provide a device for protecting the economizer during the inactivity of the automatic feeding means.

The protecting device comprises a steam separator with feed-pipe connections from its water containing portion to the boiler and to the economizer; and a steam pipe connecting its steam-containing portion to the boiler. I further provide a by-pass or water feeding means for the economizer, which by-pass is controlled independently of the automatic valve or regulator in front of the economizer, and means such as a piston valve and a float operating upon

a predetermined decrease of the level in the water-containing portion of the separator, for opening the flow passages through the steam pipe and through the by-pass. The piston valve or the like is also arranged to close the passages after the feeding means has raised the level in the water-containing portion of the separator to a predetermined desired level.

My invention is suited for all kinds of economizers but is particularly useful for the up-to-date ribbed type which has a small water space but a large heating surface so that the liability for excessive formation of steam, and exposure of heating surfaces to local heating is very great.

In the accompanying drawings, a protecting device and a boiler system to which the device is adapted, are illustrated by way of example.

In the drawings:

Fig. 1 is an axial section of the protecting device;

Fig. 2 is a section on the line II—II in Fig. 1, showing the upper end of the protecting device;

Figs. 3 and 4 are elevations of a piston valve for controlling the aforesaid flow passes, Fig. 4 being viewed at right angles to Fig. 3;

Figs. 5 and 6 are elevations illustrating, in a manner similar to Figs. 3 and 4, a bushing in which the piston valve is mounted to slide.

Fig. 7 is an elevation of a cap nut for holding the lower end of the bushing.

Fig. 8 is a section on the line VIII—VIII in Fig. 1;

Fig. 9 is a section on the line IX—IX in Fig. 2, and

Fig. 10 is a diagrammatic elevation of the boiler system.

Referring now to the drawings, and first to Fig. 10, *a* is a steam generator, here shown as a tubular boiler. *c* is an economizer which is connected to a main feed pipe *F*, and *b* is the aforesaid automatic valve or regulator which is arranged in front of the economizer *c*, and is operated by a float *B* in the boiler *a*, and a cable *C*. A feed pipe connection extends from the top of the economizer *c* to the water-containing portion of the protecting device *u* at *f*, and another feed pipe connection *f'* extends from the water-containing portion to the water space of the boiler *a*.

The steam-containing portion of the protecting device is connected to the steam space of the boiler *a* by a steam pipe *i*, to the main feed pipe *F* through a by-pass pipe *n* which opens into the

main feed pipe at a point between the automatic valve *b* and the economizer *c*; and to a subsidiary feed pipe *l*. The flow passages through the several pipes are controlled by a regulating member *q*.

The regulating member *q*, Figs. 1 to 4, here shown as a piston valve, is mounted to slide in a bushing *x*. As a matter of fact, the so-called piston valve is shown, solely by way of example, as a combined sleeve and piston valve, the sleeve portion controlling the steam passage between the boiler and the protector, and the piston portion controlling the intermittent water-supply means, to be described in greater detail hereinafter. To indicate the generic character of the valve, it will be referred to in the claims as cylindrical. The bushing is arranged in a housing *v* which is placed on a pipe *m* extending upwardly from the steam-containing space of the protecting device *u* with its lower end, and closed by a lid *v'* on its upper end.

The several pipe connections of the protecting device *u* will now be described. The feed pipe connection *f* is connected to a flanged pipe *f''*, and the feed pipe connection *f'* is connected to another flanged pipe *f'''*, in the water containing portion of the protecting device. The steam pipe *i* is connected to a flanged pipe *o* which extends from the housing *v*. The subsidiary feed pipe *l* is connected to a flanged pipe *h* which extends from the housing *v* at right angles to the steam pipe connection *o*, and the by-pass pipe *n* is connected to a flanged pipe *h'* which is diametrically opposite the pipe *h*.

The upper end of the bushing *x* is packed in the housing *v* by a cap nut *x'* and packing material *q'*. The cup nut *x'* has an opening in its web, and the web is spaced apart from the upper end of the bushing *x*. At its lower end, the bushing *x* is held by another cap nut *p*, also with an opening in its web, and a suitable packing.

The regulating member or piston valve *q*, Figs. 3 and 4, has two parallel grooves *r* in its upper portion while its lower portion *w* is hollow. *w* are holes in the hollow portion of the valve. The housing *x*, Figs. 5 and 6, has two thickened diametrically opposite portions near its upper end, with holes *y* therein in line with the openings of the water connections *h* and *h'* in the housing *v*. In its lower portion, the bushing has holes *z* in line with the opening of the steam connection *o* in the housing. The space above the upper end of the bushing *x* is connected to the steam containing portion of the protecting device by an equalizing pipe *i'*.

The means for operating the piston valve *q* include a rod *s* which extends through the opening in the cap nut *p* and through the hollow portion *w'* of the valve and is connected to the solid portion of the valve by a knuckle joint *d* at its upper end, while its lower end is pivotally connected to a double-armed lever *t* which is free to oscillate about a pin 20 in the casing of the protecting device *u*. A float *g* is suspended from the longer, and another float *g'* is suspended from the shorter arm of lever *t*, and the movement of the lever is limited by adjustable checks *k*, *k* engaging the tail end of its longer arm. The specific gravities of the floats *g* and *g'* are different. They may both be made of solid materials, of distinct specific gravities, or the float *g* may be hollow and filled 75 with water, its specific gravity being about 1.00.

Preferably, the two floats are so arranged and dimensioned that they are submerged in, and emerge from, the water in the protecting device *u* at the same time.

When for example the feed water supply is interrupted by the feed water regulator *b* (Fig. 10), automatically regulated by the boiler water level, steam is formed in the economizer *c* due to the continuous supply of heat, which steam passes upwardly to the economizer protecting device *u*. This steam lowers the water level in the water containing portion of the protecting device to such an extent that the floats *g* and *g'* push the piston *q* upwardly until, first of all, the steam passage from steam pipe *i* through connection *o*, holes *w* in the piston valve, holes *z* in the bushing *x*, the pipe *m* to the steam-containing portion of the protecting device, is opened. The steam thus can flow from the economizer protecting device and thus also from the economizer to the boiler *a*, so that in short order the same pressure exists in the economizer protecting device and in the boiler *a*.

When the piston *q* is moved upwardly still further, due to the downward displacement of the liquid, the water flows through the passage from the subsidiary feed pipe *l* through connection *h'*, holes *y*, grooves *r*, connection *h*, and by-pass pipe *n* under pressure and thence into the economizer.

The steam passage remains open until the water level is restored. Both the steam and the water passage are closed so rapidly by the piston *q* that in the economizer protecting device *u* a safety cushion of steam or gas is formed. As a consequence no water can flow from the protecting device into the boiler *a*. The movements of the piston *q* or of the lever *t* is limited by means such as the two adjustable checks or set screws *k*.

In the same manner the water in the economizer is replaced by the construction just described when loss takes place due to leakage or any other cause.

According to Fig. 10 a device 23 is disposed on the economizer protecting device known per se, for example a non-return valve 23 which can be connected by the line 24 to the steam connecting line *i* between the boiler *a* and the regulator.

When the pressure in the economizer *c* falls due to leakage, steam can flow through the non-return valve 23 through the piping *i* and 24 into the economizer protecting device. Water can thus flow from the leaky portion so that the water level in the protecting device falls. In consequence the floats *g* and *g'* move the piston *q* so that water can flow from the subsidiary feed pipe *l* into the by-pass *n* and thus into the economizer *c*.

In Figs. 1 and 2 the regulating member is shown in the position in which the water passage is just opened while the steam path is already partly opened. If desired the passages for the steam and water can be simultaneously opened or closed by the regulating member. Although it is preferable that the steam passage should be the first to be opened and last to be closed. In Fig. 9 the water passage is shown fully open.

Due to the space formed between the loosely fitting bushing *x* and the housing *v*, the bushing *x* can expand freely.

The regulating member *q* is shown in the drawings as a piston valve, but if desired can be

in the form of flat valves or rotary valves having a suitable direction of movement. Moreover separate regulating members for steam and water may be used in lieu of a common regulating member which members may be operated either separately or in common by the floats g and g' . The boss 20 of the double armed lever t is mounted freely on a spindle 21. The pin extends by means of a stuffing box through the casing. The pin in accordance with the invention is arranged also as a releasing member to be actuated from the exterior. For this purpose it is provided, as is also the boss 20, with dogs 22, entraining members, or the like. These engage loosely with one another so that the lever t can oscillate freely on the pin without rotating the spindle in the stuffing box.

The stuffing box is thereby improved so that it will be tight even at high pressures. In addition the friction of the pin in the stuffing box is avoided.

I claim:

1. In a boiler system including an economizer and means for feeding water to said boiler through said economizer in dependence on the water level in said boiler, a device for protecting said economizer during the inactivity of said feeding means, said protecting device comprising a steam separator with connections from its water containing portion to the boiler and to the economizer and a connection from its steam containing portion to the boiler, a water feeding means for said economizer controlled independently of the first said feeding means, and means operating upon a predetermined decrease of the level in said separator for opening the flow passage through said steam connection and for opening the flow passage through the second said feeding means, the last said water level responsive means being also arranged to close the flow passage through said steam connection and through the second said feeding means after this feeding means has raised the water level in the separator to a predetermined desired level.

2. In a fluid heating system including a boiler, an economizer, means for feeding water to the boiler through said economizer in dependence on the water level in said boiler, a protector for the economizer disposed in the feed passage between the boiler and the economizer, a passage connecting the protector with the steam space of said boiler, a valve in said passage, water-level responsive means in said protector operatively connected to said valve, means for feeding water to the economizer at certain times during the interval said feeding means is closed, a valve in said last-mentioned means, the last said valve being operatively connected to said water-level responsive means, said valves being so constructed and arranged that during inactivity of the first said feeding means any steam which may accumulate in the protector will be vented to the boiler and water will be fed to the economizer through the second said feeding means.

3. In a fluid heating system including a boiler, an economizer, means for feeding water to the boiler through said economizer in dependence on the water level in said boiler, a protector for the economizer disposed in the feed passage between the boiler and the economizer, a passage connecting the protector with the steam space of said boiler, a piston valve in said passage, water-level responsive means in said protector

operatively connected to said piston valve, means for feeding water to the economizer at certain times during the interval said feeding means is closed, a piston valve in said last-mentioned means, the last said piston valve being operatively connected to said water-level responsive means and said valves being so constructed and arranged that during inactivity of the first said feeding means any steam which may accumulate in the protector will be vented to the boiler and water will be fed to the economizer through the second said feeding means.

4. In a fluid heating system including a boiler, an economizer, means for feeding water to the boiler through said economizer in dependence on the water level in said boiler, a protector for the economizer disposed in the feed passage between the boiler and the economizer, a passage connecting the protector with the steam space of said boiler, a valve housing in said protector, a bushing loosely inserted in said housing for ready removal therefrom and having a port interconnecting said passage and said protector, a valve slidably in said bushing and controlling said passage, water-level responsive means in said protector operatively connected to said valve, means for feeding water to the economizer at certain times during the interval said first feeding means is closed, a second valve slidably in said bushing for controlling the said last-mentioned means, the last said valve being operatively connected to said water-level responsive means, said water-level responsive means and said valves being so constructed and arranged that during inactivity of the first said feeding means any steam which may accumulate in the boiler will be vented to the boiler and water will be fed to the economizer through the second said feeding means.

5. In a fluid heating system including a boiler, an economizer, means for feeding water to the boiler through said economizer in dependence on the water level in said boiler, a protector for the economizer disposed in the feed passage between the boiler and the economizer, a passage connecting the protector with the steam space of said boiler, a valve in said passage, means for feeding water to the economizer at certain times during the interval said feeding means is closed, a valve in said last-mentioned means, the said two valves being formed as cylindrical elements on a rod, and water-level responsive means in said protector and operatively connected to said rod for actuating said valves, said water-level responsive means and said rod and valves being so constructed and arranged that during inactivity of the first said feeding means any steam which may accumulate in the protector will be vented to the boiler and water will be fed to the economizer through the second said feeding means.

6. In a fluid heating system including a boiler, an economizer, means for feeding water to the boiler through said economizer in dependence on the water level in said boiler, a protector for the economizer disposed in the feed passage between the boiler and the economizer, a passage connecting the protector with the steam space of said boiler, a valve housing in said protector, a bushing loosely but fixedly inserted in said housing for ready removal therefrom and having openings therein, certain of which are connected with said passage, a cylindrical valve slidably in said bushing and having openings

adapted to cooperate with at least some of the openings of said bushing, the said openings co-operating to open a connection with said passage, and the said valve being adapted to control said passage, water-level responsive means in said protector operatively connected to said valve, means for feeding water to the economizer at certain times during the interval said feeding means is closed, certain other of the 10 openings in said bushing connecting with said last-mentioned means, a second cylindrical valve slidable in said bushing, and having openings therein cooperating with certain of the 15 openings in said bushing for opening a connection with and controlling said last-mentioned means, the last said valve being operatively connected to said water-level responsive means, said water-level responsive means and said valves being so constructed and arranged 20 that during inactivity of the first said feeding means any steam which may accumulate in the protector will be vented to the boiler and the water will be fed to the economizer through the second said feeding means, and the openings of 25 the said piston valves being so related to those of the bushing that under the actuation of said water-level responsive means, the steam passage will be opened before and will be closed after the second said feeding means.

30 7. In a fluid heating system including a boiler, an economizer, means for feeding water to the boiler through said economizer in dependence on the water level in said boiler, a protector for the economizer disposed in the 35 feed passage between the boiler and the economizer, a passage connecting the protector with the steam space of said boiler, a valve in said passage, means for feeding water to the economizer at certain times during the interval said feeding means is closed, a valve in said last-mentioned means, the said two valves being 40 formed as cylindrical elements on a rod, water-level responsive means in said protector and operatively connected to said rod for actuating 45 said valves, said water-level responsive means and said rod and valves being so constructed and arranged that during inactivity of the first said feeding means any steam which may accumulate 50 in the protector will be vented to the boiler and water will be fed to the economizer through the second said feeding means, and means inter-connecting the steam chamber of said protector with the outermost face of that cylindrical valve 55 which is the more remote from the interior of

the protector, for equalizing the load on the valve.

8. In a fluid heating system including a boiler, an economizer, means for feeding water to the boiler through said economizer in dependence 5 on the water level in said boiler, a protector for the economizer disposed in the feed passage between the boiler and the economizer, a passage connecting the protector with the steam space of said boiler, a valve in said passage, water-level responsive means in said protector operatively connected to said valve, means for feeding water to the economizer at certain times during the interval said feeding means is closed, a valve in said last-mentioned means, the last 15 said valve being operatively connected to said water-level responsive means and said valves being so constructed and arranged that during inactivity of the first said feeding means any steam which may accumulate in the protector 20 will be vented to the boiler and water will be fed to the economizer through the second said feeding means, the said water-level responsive means comprising control bodies having different specific weights and volumes and each extending partly into the water in said protector, a rod pivoted on said protector and pivotally connected on opposite sides of its pivotal mounting to said bodies and a second rod pivotally connected to said first rod and transmitting to 30 said valves the motion of said first rod due to variations in the relative positions of said control bodies.

9. In a boiler system including means for feeding water to said boiler, a main feed water 35 valve and an economizer feeding water in dependence on the water level in said boiler, a protector for said economizer disposed in the feed passage between the boiler and the economizer, and having steam and water-containing 40 portions, a steam passage connecting said protector with said boiler, a pipe for supplying a water-inlet of said economizer, a valve or valves in the steam-containing portion of the protector and disposed in both said steam passage 45 and said water supply pipe and connected with a controlling means depending on the water level in the protector, said valve thereby being capable of and regulating both the water flow in said pipe, and the stream flow from the protector to the boiler during the time the main water feeding valve of the economizer is closed, said controlling means comprising diving bodies 50 depending on the water level in the protector.

FRITZ WENGE. 55
